UNITED STATES PATENT OFFICE.

WILLIAM B. MURRAY, OF WASHINGTON, DISTRICT OF COLUMBIA, ASSIGNOR TO THE MILLER TRAIN CONTROL CORPORATION, OF STAUNTON, VIRGINIA, A CORPORATION OF VIRGINIA.

TRACK-CONTROL CIRCUIT.

1,180,790.

Specification of Letters Patent. Patented Apr. 25, 1916.

Original application filed July 12, 1911, Serial No. 638,108. Divided and this application filed July 27, 1912. Serial No. 711,795.

To all whom it may concern:

Be it known that I, WILLIAM B. MURRAY, a citizen of the United States, residing at Washington, in the District of Columbia, 5 have invented certain new and useful Improvements in Track-Control Circuits, of which the following is a specification.

The present invention relates to mechanically operated and electrically controlled 10 train control systems, and particularly to such systems shown and described in my co-pending application for mechanically operated and electrically controlled train control system, filed July 12, 1911, Serial No. 15 638,108, of which the present application is a division.

An important object of this invention is to provide a novel electrical system, including circuits connected with ramps which 20 mechanically operate the train stopping and signal actuating means, such operation being electrically controlled by the circuits.

Other objects and advantages of the invention will be apparent during the course 25 of the following description.

In the accompanying drawings forming a part of this specification and in which like numerals are employed to designate like parts throughout the same, Figure 1 is a 30 diagrammatic view of the track and circuits associated therewith, Fig. 2 is a side elevation of the mechanically operated and electrically controlled apparatus, Fig. 3 is an edge view of the same, Fig. 4 is a horizontal sectional view taken on line 4-4 of Fig. 2, and, Fig. 5 is a side elevation of a ramp.

In Fig. 1, the numerals 1 and 2 designate track rails, insulated at spaced intervals, as 40 shown at 3, to divide the track into a plurality of blocks of suitable length, which are designated 1', 2', 3' and 4'. Near the entrance end of each block is arranged a ramp, which is curved longitudinally in a vertical plane and formed of two ramp sections 4 and 5, which are insulated from each other, as shown at 6.

The engines or trains are run in one direction, that is from right to left, as indicated by the arrows. At the right or entrance end of the blocks 1', 2' and 3' are disposed semaphores, comprising paddles 20', 21' and 22', respectively. It is to be understood that a semaphore is placed at

the entrance end of each of the remaining 5 blocks, (not shown). The paddles are adapted to assume three positions, a horizontal to indicate danger, as shown by the paddle 20', an intermediate position to indicate caution, as shown by the paddle 21', and a lowermost position to indicate a clear track, as shown by the paddle 22'. These paddles may be either manually moved or operated by an automatic electrical control system. The ramp sections 4 and 5 are disposed near the entrance ends of the blocks and control the passage of the engine into the next block to the left. At the exit end of each block is disposed a source of current 23' connected by a wire with the rail 2 and 70 connected with the rail 1 by a wire 24'. Disposed at the entrance end of each block is a relay 25', comprising an electro-magnet 26', having its winding connected with the rails 1 and 2 by wires 27' and 28'. An armature 75 29' is disposed near the end of the electro-magnet 26' and is held adjacent the electro-magnet while the same is energized but will automatically move away from the same when the electro-magnet is deenergized. As 80 long as an engine does not enter the block, it is obvious that a circuit is closed and current will flow from one side of the source of current 23', through rail 2, through wire 28', through electro-magnet 26', through rail 85 1, and through wire 24', back to the source of current 23'. When an engine travels into the entrance end of the block, the above referred to circuit is made through the engine and the electro-magnet 26' is cut out 90 of circuit.

The numeral 23 designates a source of current having one pole electrically connected with the rail 1 and its opposite pole connected with the armature 29'. A stationary 95 contact 24 is disposed near the armature 29' and is adapted to be engaged by the same when the electro-magnet 26' is energized and disengaged when the electro-magnet is deenergized. The stationary contact 24 has 100 electrical connection with a pivoted contact segment 30^a, adapted to engage and disengage spaced stationary contacts 31^a, 32^a and 33^a. The contact segment 30^a swings in a vertical plane and is adapted to assume three 105 positions, an upper to engage contact 33^a, an intermediate position to engage both contacts 32^a and 31^a, and a lowermost position

to engage contact 31^a. This contact segment is moved synchronously with its adjacent signal paddle and has operative connection with the same through the medium of a rigid rod 34^a, having suitable pivotal connection with the paddle and the contact segment. Connected with the contact 32^a is a wire 35^a, having connection with the ramp-section 4 and connected with the contact 31^a is 5 a wire 36^a having connection with the ramp-section 5. From the description of the above referred to parts, it is obvious that when the paddle is in its horizontal position, both ramp-sections 4 and 5 are disconnected from 10 the source of current 23, when the paddle is in its intermediate position both ramp-sections have connection with the source of current, and when the paddle is in its lowermost position, the ramp-section 4 is disconnected 15 from the source of current and the ramp-section 5 connected with the same. Attention is called to the fact that the connecting and disconnecting of the ramp-sections work true with the signal paddle as 20 long as the signal paddle is true. If the signal paddle at the entrance to a block is in its lowermost position to indicate a clear block, but in fact the block is occupied, the electro-magnet 26' will be deenergized by 25 the engine cutting the same out of the track circuit and hence both of the ramp-sections 4 and 5 near the entrance end of the block will be disconnected from the source of current, although according to the position of 30 the paddle, the ramp-section 5 should have had electrical connection with said source of current.

Attention is now called to Figs. 2 and 3, wherein is shown a mechanically operated 40 and electrically controlled apparatus, which is carried by the engine. This apparatus comprises a vertically movable structure including a bar 27, the upper end of which is slidably mounted in a socket 28, rigidly 45 attached to a bracket 29, which is suitably secured to the frame-work of the engine. The lower end of the bar 27 fits within a recess formed upon one side of a shank 30 of a shoe 31. The bar 27 is insulated from the 50 shank 30 as shown at 30^b and is rigidly attached thereto by bolts 32. The shoe 31 is adapted to engage the ramps and to be elevated thereby. In order that the shoe 31 may not suffer from wear owing to its engagement with the ramps, I provide a removable block 33, which is preferably formed of hard steel. This block is mounted within a recess formed in the lower portion of the shoe 31 and is held therein by suitable means and is adapted to conduct an electric current from the ramp to the shoe 31. The bar 27 has a bracket 34 rigidly connected therewith intermediate the ends thereof, and an arm 35 is pivotally connect- 55 ed with bracket 34, as shown at 36. The

upper portion of the swinging arm 35 is provided with an enlarged head 37, through which is formed an inverted L-shaped slot 38, as shown. The head 37 carries a lateral extension or ear 39, provided with a pin 40, 70 to operate within an elongated slot 41 formed through the vertical arm of a bell-crank lever 42. This bell-crank lever is pivotally mounted upon the bracket 29, as shown at 43. An upright 44 is rigidly 75 mounted upon the bracket 29 and serves to rigidly hold a solenoid 45, having a movable core 46, which is connected to the horizontal arm of the bell-crank lever 42 through the medium of a pivotal link 47. When the 80 solenoid 45 is energized, the bell-crank lever 42 is moved to swing the arm 35 to the right, whereby a pin 48 is positioned in the vertical portion of the slot 38. The pin 48 has rigid connection with the upper end or head 85 of a swinging arm 49, pivoted as shown at 50, with the horizontal arm of a bell-crank lever 51, which is pivoted, as shown at 52, with a stationary bracket 53, preferably attached to the support or bracket 29. The 90 swinging arm 49 carries upon its outer side a laterally extending lug 54, adapted to engage a corresponding lug 55 carried by the horizontal arm of the bell-crank lever 51. The function of these lugs is to prevent the 95 arm 49 from swinging to the right with relation to the bell-crank lever 51 when such bell-crank lever is in its normal starting position.

Rigidly mounted upon the bracket 29 is 100 an upright 56, disposed to one side of the head 37, as shown. At the upper end of the upright 56 is rigidly attached a horizontal arm 57, to which is pivoted, as shown at 58, a vertically swinging lever 59, which is 105 urged upwardly by a spring 60, to engage a stop 60'. The lever 59 and associated members are disposed upon the opposite side of the bar 27 with relation to the arm 35. This lever is apertured at its free end as shown at 110 61, for connection with a cable 62, which has connection with a discharge valve 62', carried by the engine and adapted when operated to cause a whistle (not shown) disposed in the engine cab, to be sounded. This 115 is the customary whistle provided on all engines and is generally operated by the conductor or other attendant pulling a cord extending through the cars. When the lever 59 is swung downwardly the discharge valve 120 62' is operated. Pivotally mounted upon the upper end of the swinging arm 35, is a swinging arm 64, provided with an elongated slot 65, within which operates a pin 66, carried by the lever 59. The inner wall 125 of the slot 65 is provided with a recess 67, adapted to receive the pin 66, when the swinging arm 64 is swung to the right and held in this position by means to be next described. A curved arm 68 is rigidly con- 130

ected with the head 37 and serves to rigidly hold a solenoid 69, having its movable core connected with the swinging arm 64 through the medium of a pivotal link 70.

5. The shoe 31 is electrically connected with the solenoid 45 by a wire 71 and solenoid 45 is connected in series with the solenoid 69 by a wire 72. A wire 73 is connected with one end of the winding of the solenoid 69 and is connected with the bracket 53 and hence is grounded to the frame of the engine. From the description of the above referred to parts, it is obvious that the two solenoids 45 and 69 are simultaneously energized and deenergized.

The upstanding arm of the bell-crank lever 51 is suitably connected with train stopping means, to operate the same. This train stopping means is shown in my co-pending application, above referred to, as comprising means for cutting off the supply of steam and applying the brakes. In the present application such means is shown diagrammatically in the form of an air brake valve 51^a.

In the operation of the entire system, the trains are run in one direction, as illustrated in Fig. 1. To more clearly explain the operation of the system, it may be assumed that block 1' is occupied and the paddle 20' is moved to the horizontal or danger position. The block 2' is in caution condition and the paddle 21' is moved to assume its intermediate position. The block 3' is clear and the paddle 22' is moved to its lowermost position. The operation of the paddle 20', 21' and 22' may be effected manually or by electrical apparatus. When the paddles are operated manually telephonic communication is provided between the ends of the blocks so that the different operators may instruct each other when a train enters or leaves the block.

The train being in block 1', the track circuit will be closed through the train and the electro-magnet 26' cut out of circuit and deenergized. The armature 29' will then disengage contact 24, whereby current cannot flow from the source of current 23'. The paddle 20' occupying its horizontal or danger position holds the segment 30^a in its uppermost position and places the segment in engagement with the contact 33^a. The ramp-sections 4 and 5 disposed near the entrance end of the block 1' are thus disconnected from the source of current 23 by two means, namely the deenergized electro-magnet 26' and the contact segment 30^a. Attention is called to the fact that should the paddle 20' have been falsely set to indicate that the block 1' is clear, the electro-magnet 26' being still deenergized, the ramp-sections 4 and 5 could have no electrical connection with the source of current 23. As there is no train in the block 2', a track circuit will

be closed and current will flow from one side of the source of current 23' through rail 2, through wire 28', through electro-magnet 26' at the entrance end of block 2', through wire 27', and back to the source of current 23' through the wire 24'. The electro-magnet 26' at the entrance end of the block 2' is now energized and contact 24 engages the armature 29'. The paddle 21' when moved to its intermediate position, swings the contact segment 30^a to its intermediate position for engagement with both contacts 31^a and 32^a. The two ramp-sections 4 and 5 near the entrance end of block 2' both have electrical connection with the source of current 23, through armature 29', contact segment 30^a, and wires 35^a and 36^a. In connection with block 3', the above described track circuit is closed and the electro-magnet 26' near the entrance end of this block is energized. The paddle 22' assuming its lowermost position, moves the contact segment 30^a to its lowermost position, whereby the same disengages the contact 32^a but still remains in engagement with the contact 31^a. The ramp-sections 4 and 5 disposed near the entrance end of block 3' (not shown) are now in a condition to allow the train to enter the block 3', as the ramp-section 5 will have electrical connection with the source of current 23, through armature 29', segment 30^a and wire 36^a while ramp-section 4 will be disconnected from this source of current.

Assuming that an engine is entering block 3' from block 4' and traveling in the direction of the arrow, as soon as the engine moves into proximity to the ramp-sections 4 and 5 (not shown) near the entrance end of block 3', the shoe 31 will engage ramp-section 5 and a circuit will be closed for energizing the solenoids 45 and 69. When this circuit is closed, current will flow from the source of current 23, through armature 29', contact segment 30^a, lead wire 36^a, through the ramp-section 5, shoe 31, wire 71, solenoid 45, solenoid 69, wire 73, through the frame of the engine and through rail 1, back to the source of current. When the solenoid 45 is energized, it swings bell-crank lever 42 and swings the arm 35 to the right, whereby the pin 48 can only operate in the vertical portion of the inverted L-shaped slot 38. Upon further travel of the shoe 31 over the ramp-section 5, it is elevated and moves the arm 35 upwardly. It is obvious that the arm 35 cannot now upon its upward movement, effect a movement of the bell-crank lever 51. When the solenoid 69 is simultaneously energized with solenoid 45, it swings the arm 64 to cause the pin 66 to enter the recess 67, when the swinging arm 35 has been sufficiently elevated. The arm 64 does not move the lever 59 until the shoe 31 and its associated elements begin to descend and then only if

the solenoid is energized. Upon further travel of the engine, the shoe 31 engages the insulated portion 6 of the ramp, whereby the above referred to circuit is opened 5 and solenoids 45 and 69 deenergized. Upon further travel of the engine, the shoe 31 engages the ramp-section 4, which as above stated, is disconnected from the source of current. The shoe 31 and its associated 10 members now begin to descend until they disengage the ramp-sections 4 when they will again assume their normal positions.

The engine now continues its travel in block 3' and approaches the entrance end 15 of block 2'. When the shoe 31 engages ramp-section 5 disposed near the entrance end of block 2', a circuit will be closed for energizing solenoids 45 and 69. In this circuit current will flow from the source of 20 current 23, through armature 29', contact segment 30^a, lead wire 36^a, ramp-section 5, shoe 31, lead wire 71, solenoid 45, lead wire 72, solenoid 69, wire 73, the framework of the engine, and through rail 1 back to the 25 source of current. When the solenoids 45 and 69 are energized, the bell-crank lever 42 is swung to position the pin 48 in the vertical portion of the inverted L-shaped slot 38. The shoe 31 and arm 35 are now elevated but 30 the pin 48 will work idle in the vertical portion of the slot 38 and the bell-crank lever 51 will not be turned. When the arm 35 has reached its uppermost position, the pin 66 will be disposed in alignment with 35 the recess 67 of swinging arm 64. The solenoid 69 being energized, the arm 64 is swung so that the pin 66 is disposed within the recess 67 and held fast therein. When the shoe 31 engages the insulation 6, the above 40 referred to circuit is opened and solenoids 45 and 69 deenergized. As above stated, both ramp-sections 4 and 5 have electrical connection with the source of current. The shoe 31 now engages ramp-section 4, whereby 45 a circuit is closed to again energize the solenoids 45 and 69. In this circuit, current will flow from the source of current 23 at the entrance end of block 2', through armature 29', contact segment 30^a, lead wire 35^a, 50 a ramp-section 4, shoe 31, lead wire 71, solenoid 45, wire 72, solenoid 69, wire 73, the frame-work of the engine, and through the rail 1, back to the source of current. The solenoid 69 being now energized, the pin 66 55 is held fast within the recess 67. The shoe 31 continuing its travel over the ramp-section 4, begins to descend, carrying with it the arm 64 and associated members. The arm 64 will now swing lever 59 downwardly. 60 The cable 62 attached to this lever is pulled and the exhaust valve 62' is operated to sound the whistle in the engine cab, to indicate caution, whereby the engineer is informed that the block 1' is occupied.

65 The ramp-sections 4 and 5 near the en-

trance end of block 1' are both disconnected from the source of current 23. When the engine moves into proximity to these ramp-sections the shoe 31 engages the ramp-section 5 and is elevated by traveling along 70 the same. No circuit is now closed to energize the solenoids 45 and 69. The pin 48 remains in the horizontal portion of the inverted L-shaped slot 38, whereby when the shoe 31 moves the arm 35, upwardly, the 75 arm 49 will be elevated and bell-crank lever 51 swung. This movement of the bell-crank lever 51 actuates the air brake valve to stop the engine.

It is to be understood that the form of my 80 invention herewith shown and described is to be taken as a preferred example of the same and that certain changes in the shape, size, and arrangement of parts may be resorted to without departing from the spirit 85 of the invention or the scope of the subjoined claims.

Having thus described my invention, I claim:

1. In a train control system, a track divided into blocks, a source of current having electrical connection with the rails of the block, a relay having electrical connection with said rails, a ramp curved longitudinally in a vertical plane and adapted to move an 90 element carried by the train disposed near the entrance end of the block to one side of one of the rails and including a plurality of ramp-sections which are rigidly connected by insulating means to provide a continuous 95 engaging surface, and partial circuits including a source of current having connection with the ramp-sections and opened and closed by said relay.

2. In a train control system, a track divided into blocks, a source of current, a ramp curved longitudinally in a vertical plane disposed near the entrance end of the block, adapted to move an element carried by a train, arranged to one side of one of 100 the track rails and formed of a plurality of ramp-sections which are permanently connected by insulating means to form a continuous engaging surface, means for connecting and disconnecting the ramp-sections 115 with and from the source of current, and means including a track block circuit operating independently of the first named means, for controlling the connection between said ramp-sections and source of current.

3. In a train control system, a track divided into blocks, a ramp curved longitudinally in a vertical plane disposed near the entrance end of each block upon one side of 125 one of the track rails to move an element carried by the train, a source of current, means for connecting and disconnecting the ramp with and from the source of current, and separate means to connect and discon- 130

nect the ramp with and from the source of current, including a relay and a track circuit connected with the relay.

4. In a train control system, a track, a ramp disposed near the same, a source of current independently operating relay and switch for connecting and disconnecting the ramp with and from said source of current at a plurality of different points, and a track circuit connected with the relay.

5. In a train control system, a track, a ramp disposed near the same, a source of current, a relay and switch for connecting and disconnecting the ramp with and from said source of current, a track circuit connected with the relay, track signaling means, and means for operating the switch from said track signaling means.

6. In a train control system, a track divided into blocks, ramp-sections insulated from each other and disposed near the entrance end of the block, a relay, a track circuit connected with the relay, a source of current having one pole connected with the rail of the track and its other pole connected with the armature of the relay, a contact to coöperate with the armature, a contact arm having electrical connection with the contact, a plurality of contacts to be engaged and disengaged by the contact arm, and means electrically connecting said plurality of contacts and ramp-sections.

7. In a train control system, a track divided by insulating means into blocks, a ramp disposed near the entrance end of the block, formed of a plurality of insulated ramp-sections and arranged to one side of the track rail to move an element carried by the train, a source of current having one pole thereof electrically connected with the track rail and its opposite pole adapted to be connected with the ramp-sections, means for controlling the electrical connection between the source of current and the ramp-sections, a source of current connected across the rails in the block, and a relay connected across the rails in said block to disconnect the ramp-sections from the first named source of current when said relay is de-50 energized.

8. In a train control system, a track divided by insulating means into blocks, a ramp curved longitudinally in a vertical plane and adapted to move an element carried by the train and disposed near the entrance end of the block to one side of one of the rails and formed of a plurality of insulated ramp-sections, which are rigidly connected by insulating means to provide a continuous engaging surface, a source of current having one pole thereof electrically connected with one of the rails, and separate devices to connect and disconnect the ramp-sections with and from the opposite pole of 65 the source of current.

9. In a train control system, a track divided by insulating means into blocks, ramp-sections insulated from each other and disposed near the entrance end of each block, a source of current, means to connect and disconnect the source of current with and from the ramp-sections, means operated upon the entrance of a vehicle into the block to disconnect said source of current from the ramp-sections at a different point, 75 and mechanically operated and electrically controlled apparatus carried by the vehicle to coöperate with said ramp-sections.

10. In a train control system, a track divided by insulating means into blocks, a ramp disposed near the entrance end of each block, a source of current, means to connect and disconnect the source of current with and from said ramp, means operated upon the entrance of a vehicle into the block to 85 disconnect said source of current from said ramp at a different point, and mechanically operated and electrically controlled apparatus carried by the vehicle to coöperate with the ramp, substantially as described. 90

11. In a train control system, a track divided by insulating means into blocks, a ramp including insulated ramp-sections adapted to move an element carried by the train and disposed near the entrance end of the block upon one side of the track rail, a source of current having one pole thereof electrically connected with the track rail, means to control the electrical connection between the opposite pole of the source of 100 current and said ramp-sections, a track signal means disposed near the entrance end of the block, and operative connections between the track signal means and the controlling means, so that they operate together. 105

12. In a train control system, a track divided by insulating means into blocks, ramp-sections insulated from each other and disposed near the entrance end of each block, a source of current having one pole thereof 110 electrically connected with the rail of the block, means to control the electrical connection between the opposite pole of the source of current and said ramp-sections, a track signal disposed near the entrance end of 115 each block, operative connection between said track signal and means so that they operate together, means operated upon the entrance of a vehicle into a block to disconnect the ramp-sections near the entrance end 120 of said block from the source of current, and mechanically operated and electrically controlled apparatus carried by the vehicle to coöperate with the ramp-sections.

13. In a train control system, a track divided by insulating means into blocks, a ramp disposed suitably near the entrance end of the block, a source of current, a circuit between the source of current and the ramp and adapted to be opened at a plu-130

rality of points, track circuit controlled means for opening the circuit at one point, and track signal operated means for opening the circuit at another point.

- 5 14. In a train control system, a track divided by insulating means into blocks, a ramp disposed near the entrance end of the block upon one side of the track rail and formed of a plurality of insulated ramp-
10 sections adapted to move an element carried by the train, a source of current, means connecting and disconnecting each ramp-section

with and from the source of current depending upon the condition of the block, and automatic means for disconnecting the 15 ramp-sections from the source of current upon the entrance of a train into the block.

In testimony whereof I affix my signature in presence of two witnesses.
